UNITED STATES PATENT OFFICE.

FRANKLIN M. COSSITT AND LEWIS D. CASTOR, OF BINGHAMTON, NEW YORK, ASSIGNEES TO ANSCO COMPANY, OF BINGHAMTON, NEW YORK.

APPARATUS FOR COATING AND DRYING PHOTOGRAPHIC PAPERS, PHOTOGRAPHIC FILM SUPPORT AND SIMILAR MANUFACTURES.

1,171,321.

Specification of Letters Patent. Patented Feb. 8, 1916.

Application filed May 14, 1914. Serial No. 838,447.

To all whom it may concern:

Be it known that we, FRANKLIN M. COSSITT and LEWIS D. CASTOR, both citizens of the United States, and both residents of the city of Binghamton, county of Broome, and State of New York, have invented a new and Improved Apparatus for Coating and Drying Photographic Papers, Photographic Film Support and Similar Manufactures, of which the following is a specification, reference being had to the accompanying drawings.

The invention consists in an apparatus adapted to apply upon one of the surfaces of a continuously moving web, sheet or film a coating of suitable fluent material and setting, drying or hardening the coating, all of the operations being performed in a partial vacuum. The apparatus is provided with means whereby the fluent coating material may be automatically and continuously supplied to a suitable coating apparatus, the level of the coating material within the apparatus being automatically maintained, and provision is also made for continuously removing from the vacuum chamber the vapors of the volatile solvents and condensing them for recovery. The uncoated sheet, web or film and also the coated and dried product may be inclosed within the chamber or may be exterior thereto and passed thereinto and therefrom through suitable airtight, or sufficiently air tight devices.

The object we have in view is the production of photographic products, paper, film and the like, sensitive to light, in which the sheet, web or film will be the support merely for a photographically sensitive coating or layer applied to one of the surfaces. Therefore in the production of this class of goods, various problems are presented, which are admirably solved by our apparatus, the peculiar nature of which is fully set forth in an application Serial No. 838,446, filed by us concurrently herewith, in which we describe and claim our new process.

Referring to the drawings, Figure 1 illustrates an elevation, partly broken away, of one form of apparatus embodying our invention; Fig. 2 illustrates a longitudinal vertical section of one form of coating apparatus; Fig. 3 illustrates a transverse vertical sectional view of that which is shown in Fig. 2.

1 represents a frame which may be made of any suitable material.

2 is one of a pair of brackets provided with a journal 3 upon which is rotatably supported upon a shaft 4 a coil or roll 5 of the web, sheet or film (hereinafter called the stock) to be coated. It passes in the direction of the arrow over a series of guide and tension rollers 6, 6, 6, which may be of any preferred material and construction. They are shown in the drawings as having a rubber, felt or other surface. This, however, is immaterial. The web passes through one of the walls 7 of the vacuum chamber 8 within which chamber it passes over a guide roller 9 which in the example shown has a stock-protecting rubber, felt or other surface similar to that of the rollers 6. The stock passes thence under a coating roller 10 which is located in a coating trough 11 and applies the coating to one side only of the stock, the detail of one form of which will be described later and which is supplied with the sensitive or other coating from a reservoir 12 which may be outside of the vacuum chamber as illustrated, or inside of it as preferred. After passing under the coating roller the stock 5 extends upwardly still within the vacuum chamber over a guide roller 13 and thence through an extension (preferably although not necessarily horizontal) of the vacuum chamber 8. In its transit it is supported in any suitable manner. We prefer a series of rollers 14 because when they are employed, more free circulation of air currents about the coated stock will be secured than if a continuous table is employed, but a series of bars or slat work or for that matter a supporting surface of any kind may be employed, provided it makes contact only with the uncoated side of the stock. We impose no limitation in this respect and for certain manufactures no support whatever will be necessary.

In the vacuum chamber is an exhaust tube 15 provided with openings 16 shown in this instance as made in its under surface. They may, however, be located at any preferred part. This exhaust tube is in open connection with a series of pipes 17 which connect with a longitudinal pipe 18 which in turn connects with a pipe 19 leading to a vacuum pump 20 run by a suitable electric motor or other power as indicated and from the pump

the exhaust pipe extends to a condenser indicated at 21.

After the stock 5 has passed through the vacuum chamber which is made of such length as is necessary to sufficiently dry the coating upon the stock, it may pass through the opposite wall of the vacuum chamber as at 22 over a guide roller 23 and is wound up as at 24 upon a shaft which is driven by 10 belting 25 connecting with any suitable source of power 26 in a manner well known.

We show duplicate brackets 27, 27, upon the frame 1 because it will sometimes be convenient to run more than one strip or band 15 of stock through the machine at the same time and for this purpose the guide rollers, coating roller, vacuum chamber and all its appurtenances may be made of such width as will accommodate one or more strips of 20 stock of any preferred width.

The detail of one form of coating apparatus is illustrated in Figs. 2 and 3. The coating trough 28 is supported at one end by a fulcrum 29 or other suitable support. At 25 its other end it rests upon the inner end 30 of a lever 31 provided with an adjustable counterbalance 32. The lever is pivoted as at 33 upon a bracket 34. The opening 35 through which the lever passes is made sufficiently airtight in any suitable manner as by a sliding sealing device 35. The pipe 36 connected with the reservoir 12 supplies the coating material which flows in the direction of the arrow in Fig. 2. Its lower end 35 is turned upwardly as shown and seals against the under side of the top which partially covers the coating trough when the trough is full as shown best in Fig. 2. The coating trough 28 rests within an exterior 40 fixed trough or bath 37 which may be heated in any preferred manner so as to maintain the coating material at such temperature as desired.

In order that the insucking of air owing 45 to the vacuum within the vacuum chamber may be prevented or reduced to a negligible degree and yet the stock not be injured in its passage through the walls of the vacuum chamber, we prefer to provide the openings 50 through which the stock enters and passes from the vacuum chamber with suitable sufficiently airtight devices shown at 38 and 38^a in Fig. 3. The upper one 38 may be made of any preferred material. Its rounded edge 55 which engages with the stock may, if desired, be covered with some suitable non-abrasive material, as, for instance, closely woven felt or plush, not shown. The lower one 38^a may be similarly constructed but 60 we prefer to make it of relatively soft rubber as indicated. The surface which comes in contact with the stock may also be covered with protective material. These parts being separated the end of the web may be 65 passed between them into the vacuum cham-

ber, then being readjusted and fastened as by set screws and washer shown, the web may be so closely held between the opposed edges of the parts referred to as to reduce leakage of air to a negligible amount and yet not injure or scratch the surface of the stock. 70

Many useful details of construction are not illustrated nor described for they form no essential part of the invention. We will 75 state, however, that in order to facilitate the threading of the leading end of the stock through the machine, we prefer to have removable sections 40 (see Fig. 1) in the upper wall of the vacuum chamber so that 80 ready access to its interior may be secured. The edges of these removable sections may beneficially be provided with some suitable sealing material, as, for instance, rubber gaskets, so as to secure the requisite air-tightness. 85

The operation is as follows: The cover sections 40 are removed from the vacuum chamber, the stock 5 is threaded through the machine as described and the leading end of it made fast to the winding up device. The covers 40 are then replaced. The coating material, sensitized or otherwise as the case may be, is then allowed to flow from the reservoir 12 into the coating trough. 95 As the trough gradually fills its weight is increased so that it will depress the counterpoise 32 which is adjusted upon the lever 31 as conditions may require. When the coating trough is sufficiently full, it will have 100 swung downwardly so far that the upturned end of the fixed pipe 36 will come in contact with the cover of the trough as above stated and thus act as a valve to cut off the further incoming of the coating material. 105 The vacuum pump is now started and owing to the relatively small space inclosed within the vacuum chamber, the rarefaction of the air is quickly accomplished. The degree of vacuum requisite for successful operation 110 will depend upon the character of the coating material, *i. e.*, the volatility of the solvents employed, its viscosity, the speed with which the machine is run, the length of the vacuum chamber and to some extent also 115 upon the character of the stock being treated. Therefore no fixed degree of vacuum can be stated, but for ordinary purposes from 10 to 15 inches will be sufficient. When the desired vacuum has been established, 120 which may be indicated by any suitable gage not shown, the apparatus is started and the winding up device which is positively driven will draw the stock through the apparatus at the determined speed. During its transit 125 it will have become coated, the coating set and sufficiently dried or hardened to permit the finished product to be coiled up as shown in a roll 24.

Especial attention is called to the fact that 130

inasmuch as the coating trough in which the coating material is placed is itself within the vacuum chamber, there will be no bubbles in it for owing to the reduction of atmospheric pressure due to the vacuum they will 5 instantly come to the surface, break and disappear and if by any possibility a bubble should here and there be taken up upon the surface of the traveling stock, it will instantly 10 break and owing to the then fluent condition of the coating material, the spot where the bubble was will immediately close or be flowed over, thus producing a smooth surface.

15 Owing to the presence of the vacuum, i.e., the relief of atmospheric pressure, the volatility of the solvents will be very greatly increased, so that the coating upon the stock will almost immediately set and quickly 20 thereafter dry or harden, so that by the time it reaches the end of the vacuum chamber it will be in condition to be coiled up for use or storage.

We call special attention to the fact that 25 the exhaust from the vacuum chamber will obviously be very greatly reduced in volume as compared with the volume of air that is necessarily present where a blower or other means is employed for generating drying 30 air currents as heretofore customary in the manufacture of the products we contemplate, so that the expense of condensation under our system is materially lessened because instead of there being a large volume 35 of air but slightly impregnated with the vapors of the volatile solvents, there is a small volume only and it is heavily surcharged therewith and thus the expense of refrigeration is very greatly reduced.

40 We have illustrated the reservoir and supply and take up roller as located outside of the vacuum chamber because in ordinary apparatus this will be the most feasible construction, but obviously these features may 45 some or all of them be inclosed within the vacuum chamber. The fact that the stock is dry and hard and that it does not encounter the coating material until it is within the vacuum chamber enables us to pass it 50 through airtight, or sufficiently airtight devices, as described, from the exterior to the interior of the chamber and vice versa without scratching or otherwise injuring the surface of the stock. Of course if the coating 55 material be sensitive to light and the reservoir be upon the outside of the vacuum chamber, it will be necessary to provide suitable means, now well known and not shown, to prevent the contents of the reservoir 60 from becoming light struck.

The apparatus we have hereinabove described and illustrated is one form only in which our invention may be embodied and therefore we do not limit ourselves to the 65 details above described and illustrated.

We claim:

1. In a coating and drying apparatus the combination of a vacuum chamber, means to create and maintain the vacuum in the chamber, coating devices adapted to apply the coating material to one side only of the stock, supporting and guiding devices for the coated stock located in the vacuum chamber and adapted to maintain the coated side of the stock free from contact with other surfaces, and means to move the stock first to the coating devices and then away therefrom through the vacuum chamber.

2. In a coating and drying apparatus the combination of a vacuum chamber, means to create and maintain the vacuum in the chamber, coating devices adapted to apply the coating material to one side only of the stock, means to automatically maintain the level of the coating material within the coating tank, supporting and guiding devices for the coated stock located in the vacuum chamber and adapted to maintain the coated side of the stock free from contact with other surfaces, and means to continuously move the stock to the coating devices, then through the vacuum chamber and away therefrom.

3. In a coating and drying apparatus the combination of a vacuum chamber, means to create and maintain the vacuum in the chamber, a condenser connected with said means, coating devices adapted to apply the coating material to one side only of the stock, supporting and guiding devices for the coated stock located in the vacuum chamber and adapted to maintain the coated side of the stock free from contact with other surfaces, and means to continuously advance the stock first to the coating devices and then away therefrom through the vacuum chamber.

4. In a coating and drying apparatus the combination of a vacuum chamber, means to create and maintain the vacuum in the chamber, coating devices adapted to apply the coating material to one side only of the stock, means to automatically supply and determine the level of the coating material within the tank, and means to continuously move the stock first to the coating devices and then away therefrom through the vacuum chamber.

5. In a coating and drying apparatus the combination of a vacuum chamber provided with openings in its walls for the entrance and exit of the stock, devices to retard the suction of air at the said openings, means to create and maintain a vacuum in the chamber, coating devices, supporting and guiding devices for the coated stock located in the vacuum chamber and adapted to maintain the coated side of the stock free from contact with other surfaces, and means to continuously move the stock from the ex-

terior of the vacuum chamber through its wall to the coating devices, then through the vacuum chamber, and then through its wall to the exterior thereof.

5 6. In a coating and drying apparatus the combination of a vacuum chamber provided with openings in its walls for the entrance and exit of the stock, devices to retard the suction of air at the said openings, means 10 to create and maintain a vacuum within said chamber, coating devices adapted to apply the coating material to one side only of the stock, and means to continuously move the

stock from the exterior of the vacuum chamber through its wall to the coating devices, 15 then through the vacuum chamber and then through its wall to the exterior thereof.

In testimony whereof we have signed our names to this specification in the presence of two subscribing witnesses.

FRANKLIN M. COSSITT.
LEWIS D. CASTOR.
